BAGGAGE-RACK.

1,069,620.

Specification of Letters Patent.

Patented Aug. 5, 1913.

Application filed February 7, 1912. Serial No. 676,040.

To all whom it may concern:

Be it known that I, PETER N. LANDINE, a citizen of the United States, residing at Milford, New Haven county, State of Connecticut, have invented certain new and useful Improvements in Baggage-Racks, of which the following is a full, clear, and exact description:

My invention relates to car racks; that is, racks which are arranged to run along the side of a passenger car for the purpose of carrying baggage, etc.

In the present instance, my invention has for its object an improved unit arrangement whereby the rack is made up in unit sections of certain lengths which may be quickly and accurately assembled rigidly in place.

Another object of the invention is to make the several units adjustable within a sufficient range to guarantee the proper fitting of the parts in the event the main supporting brackets should not be correspondingly spaced.

While my rack is of particular utility when employed in cars, it is obvious that its use is not limited thereto.

In the drawings, Figure 1 is a top plan view of my improved rack. Fig. 2 is an end elevation of one of the brackets. Fig. 3 is a relatively enlarged detail view, partly in section. Fig. 4 is a view of a single detail. Fig. 5 is an end view of one shelf unit.

1-1 are the main supporting brackets, each being provided with a suitable base portion or portions designed to be screwed to a supporting wall where the rack is to be placed. The design of each bracket may be varied at will. Each supporting shelf or unit is arranged to be inserted and secured between two adjacent brackets 1-1, and the construction is such that the brackets 1-1 may be first separately applied to the wall, after which each individual shelf unit may be inserted or removed at will without bending or injuring either of said brackets or any other part of the rack. In Fig. 1, I have shown one complete shelf unit and parts of two other shelf units in line with the first one and rigidly connected up as said parts would appear in use, whereby it will be seen that a rack of any length and comprising as many units as desired, may be constructed.

The work of applying the brackets 1-1

to the supporting wall is seldom so accurately and carefully done that all of the brackets (where more than one unit is to be used) are spaced apart to exactly the same extent. Accordingly, it is most important that some adjusting means be provided whereby the several shelf units may be inserted between these differently spaced brackets and attached thereto; said adjusting means being also so designed and constructed that difference in adjustment between various brackets will not be observable to the eye. Again, this construction should be such that every part of the rack may be rigidly connected to every other part because, where racks are used in cars, they are subjected to such severe vibration that unless rigidly held, said vibration will soon bring disastrous results. Each bracket 1 is provided with a plurality of transverse bores which line up with the main supporting bars of the rack units as hereinafter described. In the drawings said brackets are shown as provided with three bores 2-2. Each of these bores is threaded.

As to the shelf units, in the particular form shown herein, each of them is preferably provided with a plurality of parallel main supporting bars 3-3. These main supporting bars 3-3 are connected by parallel bars 4-4. These bars, in the particular form shown, are L-shaped, although this is not material. The bars 4 carry a suitable number of light grid bars 5-5 provided in any suitable number and arranged parallel to the main supporting bars 3-3. The grid bars 5-5 are usually somewhat shorter than the main supporting bars 3-3, and the main supporting bars should preferably be slightly shorter than the intended spacing between the brackets 1-1.

The means for connecting the shelf units with the brackets 1-1 comprises screw-threaded coupling sleeves 6 arranged at the ends of the main supporting bars 3-3. The particular construction of these sleeves is important in that the same should be capable of not only rigidly connecting the ends of the main supporting bars with the brackets 1-1, but should also be capable of doing this even though the spacing of said brackets is not uniform. As shown in Figs. 3 and 4, the sleeve 6 is provided with a short external thread on its outer end, the

external threaded portion of the sleeve 6 being reduced somewhat in diameter so as to form an abutment shoulder at the base of the thread. The bore of the sleeve 6 is likewise threaded for about half its length commencing from the outer end. The balance of the inside bore of each sleeve is somewhat enlarged so that it will freely pass over the end of its main supporting bar 3. The end 5 of the main supporting bar designed to receive the sleeve 6 is threaded to correspond with the threaded bore of said sleeve, the sleeve and bar, therefore, having a positive interlocking engagement and the sleeve being longitudinally adjustable on its bar. The length of the external threaded portion of the sleeve 6 is preferably slightly less than one-half the thickness of that part of the bracket into which the sleeve is 10 designed to screw.

To assemble the various parts of the rack in place, the separate brackets are first secured in position upon the supporting wall at approximately the proper spacing. The 15 shelf units are then inserted between the racks, each of the sleeves 6—6 being screwed onto the ends of the main supporting bars 3—3 to a sufficient extent to permit the unit to be slipped in position between those two brackets which are to support said unit. The sleeves 6 are then unscrewed from the supporting rods 3 and simultaneously 20 screwed into the threaded bores in the brackets 1. When the sleeves have been 25 screwed up tightly into the brackets 1, it follows that each shelf unit will be rigidly connected with the brackets 1—1 at each end thereof. This application and assemblage of the various parts may be quickly and 30 easily effected. It should be understood, of course, that it is preferable that the outside of each sleeve 6 should be suitably designed to take some sort of wrench suitable for permitting the sleeves to be screwed tightly 35 into place. In the drawings I have shown a part of the external wall of the sleeve of hexagonal cross sectional outline, which furnishes both a pleasing ornamentation and a useful gripping surface for an ordinary 40 wrench. Inasmuch as the inner end of each sleeve extends well over and beyond the threaded portion of the particular supporting bar with which it is associated, it follows that each sleeve may be adjusted 45 longitudinally on said supporting rod to a very substantial degree without exposing the threaded portion of the rod, which is exceedingly desirable where the overall length of any particular rack unit must of necessity 50 be increased to span the space between two brackets which may be applied to the wall at a greater spacing than originally designed. When such adjustment is effected, it is impossible to detect the same because 55 the unthreaded part of each coupling sleeve

will still overstand the threaded portion of its supporting bar.

In the particular form of shelf unit shown, which, viewed from the end, is L-shaped, the design serves to very substantially stiffen the whole rack throughout, and while it is not necessary that the short upright portion of the shelf be provided in all forms of the invention, it is desirable for the foregoing reason and for the further 75 reason that it tends to prevent baggage from sliding back upon the shelf and scratching the woodwork of the supporting wall.

What I claim is:

1. In a baggage rack of the character described, a plurality of supporting brackets, a shelf arranged to be secured between said brackets and including a main supporting bar, with means for securing said shelf to 80 said brackets including a coupling member adjustably mounted on said bar so as to be adjustable longitudinally thereof and held against longitudinal movement thereon in various positions of adjustment, said 85 coupling member being arranged to interlock with one of said brackets.

2. In a baggage rack of the character described, a plurality of brackets, a shelf arranged between said brackets and comprising a plurality of main supporting bars with independent coupling sleeves carried by said bars and arranged to interlock with said brackets, and a screw-thread connection between each sleeve and its supporting bar 90 and between each sleeve and the adjacent part of the bracket.

3. In a baggage rack of the character described, a plurality of brackets, a shelf arranged between said brackets and comprising a plurality of main supporting bars with independent coupling sleeves carried by said bars and arranged to interlock with said brackets, and a screw-thread connection between each sleeve and its supporting bar 100 and between each sleeve and the adjacent part of the bracket, said sleeve having an unthreaded portion projecting over the supporting bar carrying said sleeve.

4. In a baggage rack of the character described, a plurality of brackets, a shelf arranged between said brackets and comprising a plurality of main supporting bars with independent coupling sleeves carried by said bars and arranged to interlock with said 110 brackets, a screw-thread connection between each sleeve and its supporting bar and between each sleeve and the adjacent part of the bracket, said sleeve having an unthreaded portion projecting over the supporting bar carrying said sleeve, and an abutment shoulder on said sleeve on its outer side at the rear of the thread arranged to connect with said bracket.

5. In a baggage rack of the character de- 130

scribed, a plurality of supporting brackets, a shelf arranged to be secured between said brackets and including a main supporting bar, with means for securing said shelf to said brackets including one coupling member adjustably mounted on each end of said bar so as to be adjustable longitudinally thereof and held against longitudinal movement thereon in various positions of adjustment, said coupling members being arranged to interlock with said brackets.

6. In a baggage rack of the character described, a plurality of brackets each provided with spaced threaded apertures in longitudinal alinement, a shelf arranged to be secured between said brackets and comprising a plurality of main supporting bars having threaded ends in alinement with said bracket apertures, and a plurality of independent coupling members having threaded

engagement with the ends of said supporting bars and with said bracket apertures.

7. In a baggage rack of the character described, a plurality of longitudinally alined brackets each provided with a plurality of apertures in longitudinal alinement, a plurality of shelf units arranged to be secured between adjacent brackets, each unit embodying a plurality of main supporting bars having their ends threaded and in alinement with said bracket apertures, and a plurality of independent coupling members each engaging with and adjustable longitudinally of a bracket aperture and having an adjustable threaded engagement with the end of a supporting bar.
